G. BLUMBERG & J. A. BUTKUS.
ELECTRIC CLOCK.
APPLICATION FILED OCT. 13, 1915.

1,242,132.

Patented Oct. 9, 1917.

UNITED STATES PATENT OFFICE.

GUSTAV BLUMBERG AND JOHN A. BUTKUS, OF BALTIMORE, MARYLAND.

ELECTRIC CLOCK.

1,242,132.

Specification of Letters Patent.

Patented Oct. 9, 1917.

Application filed October 13, 1915. Serial No. 55,683.

To all whom it may concern:

Be it known that we, GUSTAV BLUMBERG and JOHN A. BUTKUS, citizens of the United States, residing at Baltimore, in the State 5 of Maryland, have invented certain new and useful Improvements in Electric Clocks; and we do hereby declare the following to be a full, clear, and exact description of the invention, such as will enable others skilled 10 in the art to which it appertains to make and use the same.

Our invention relates to electric clocks, such as are complete in themselves and require no connection with a central clock or 15 an outside source of electricity. The object of our invention is to produce an electric clock which shall be entirely devoid of springs in the time train and which shall be simple, cheap, reliable and in which the 20 electrical mechanism can be quickly removed from the time mechanism for examination, renewal or repairs.

In the drawings:

Figure 1, is a front view of the time train 25 of our improved clock showing the electrical mechanism attached;

Fig. 2, is a side view of Fig. 1 looking in the direction of the arrow 2, some of the parts being omitted;

Fig. 3, is a view of Fig. 1 looking in the direction of the arrow 3, some of the parts being omitted;

Fig. 4, is a diagram of the connections of our improved clock; and

Fig. 5, is a detail view of certain parts.

The mechanism of our improved clock consists of two plates 10 and 11 which are formed with a circular rim and a five pointed star such as 12 formed integrally 40 therewith. These plates are kept in proper relation to the back board of the case in any approved manner.

The case, means for supporting the batteries and the connectors for the batteries 45 are fully illustrated and described in an application for United States Letters Patent Serial No. 55682 filed October 13th, 1915, and said parts will not be hereinafter referred to.

The plates 10 and 11 support an ordinary time train provided with hands such as

14—14. The time train also has an ordinary pendulum wire such as 15 to which is attached a pendulum not shown. All parts of the time train being old and well known 55 will not be further illustrated or described.

A plate such as 16 is secured to the rear plate 10. The plate 16 extends toward the right and is provided with a downward extension 17 to which is secured the sole- 60 noid 18.

The solenoid 18 is formed with two insulating end pieces 19 provided with a central hole and joined together by an insulating tube not shown. The ends 19—19 are se- 65 cured to the extension 17 by the screws 20—20. The solenoid 18 is wound with a plurality of turns of wire of any suitable size and the ends 21 are brought through the lower end piece 19 of the solenoid. 70

A condenser consisting of two plates 22 and 23, (see Fig. 4), is wound in cylindrical form as shown at 24 in Figs. 1 and 3 and provided with terminals 25 and 26 by which the condenser is secured to the ends 19—19 75 by the screws 27—27.

A core such as 28 preferably formed of soft iron or steel moves freely in the tube joining the ends 19—19 of the solenoid. The upper end of the core 28 is reduced in 80 size and provided with a slot 29. A pin such as 30 fits tightly in holes provided in the upper slotted end of the core 28 and a link such as 31 is mounted on the pin 30 in the slot 29. The upper end of the link 31 is 85 provided with a slot 32 and with holes in which fits tightly the pin 33.

A lever 34 has one end mounted on the pin 33 and works freely in the slot 32. The other end of the lever 34 is revolvably mounted on the pintle 35 of the clock train. A ratchet wheel 36 is rigidly mounted on the pintle 35 and a pawl 37 is pivotally mounted on the pin 38 which is secured to the lever 34. A spring 39 keeps the pawl 37 in contact with the teeth of the ratchet wheel 36. A second pawl such as 40 pivotally mounted on the pintle 41 may have its point kept in contact with the teeth of the ratchet wheel 36 in any approved manner in order to prevent the ratchet wheel 36 from being turned 95 backwardly. The pintle 35 is also provided 100

with other gear wheels, not shown, which form part of the time train.

A lever such as 42 is pivotally mounted on the screw 43, and the latter is supported on the plate 16. The portion of the lever surrounding the screw 43 is substantially circular in shape and is provided with a notch 44 for a purpose hereinafter explained. The lever 42 extends upwardly and toward the left, as shown in Fig. 1, and extends over the pin 45 secured in the lever 34. The lever 42 is provided with an arm 46 extending toward the left. A spring 47, secured by the screw 48 to a flange 49 provided on the plate 16, bears against the circular portion of the lever 42 for a purpose hereinafter explained. A plate 50 is secured to the insulation 51 by screws such as 52—52 and the said insulation is secured to the plate 16 in any approved manner.

A spring 53 is secured by the rivets 54 to the plate 50 and the upper end of said spring is located to make contact with the arm 46 of the lever 42 when said arm 46 is moved downwardly as hereinafter explained.

The electrical connections of our improved clock are as follows: (see Fig. 4).

The battery 55 has one terminal connected to the plate 50 and the other terminal to one terminal of the solenoid 18. The other terminal of the solenoid 18 is connected to the plate 16 and through said plate to the arm 46 of the lever 42.

The plate 22 of the condenser is connected through the plate 16 to one terminal of the solenoid 18 and to the lever 42. The other plate 23 of the condenser is connected to the plate 50 and to one terminal of the battery.

The operation of our improved clock is as follows:

When the parts are in the positions shown in the figures, the weight of the core 28 will be acting through the link 31 on the lever 34 and the latter acting through the pawl 37 will turn the ratchet wheel 36 in the direction of the arrow 56 in Fig. 1, and thus move the time train.

As the core 28 continues to move downwardly under the force of gravity, the lever 34 will also continue to move downwardly and the pin 45 will move from contact with the lever 42. The lever 42 will not drop because the friction produced by the pressure of the spring 47 against the circular portion of said lever is sufficient to prevent said lever 42 from dropping.

The core 28 will continue to move downwardly until the pin 45 strikes the arm 46 of said lever and moves same downwardly until the bent portion 57 of the spring 47 passes over end 44 of the circular portion of the lever 42.

The spring 47 then forces the arm 46 into contact with the spring 53, a current of elec-

tricity then flows through the solenoid 18, 65 the core 28 is attracted upwardly to the position shown in Fig. 1 and the pawl 37 co-acting with the ratchet wheel 36 prevents the said core from dropping except at the rate determined by the oscillation of the pendulum. As the core 28 moves upwardly, the pin 45 will then strike the lever 42 and move the arm 46 from contact with the spring 53. This will terminate the flow of electricity through the solenoid 18. The same cycle of 75 operations is repeated indefinitely.

When the lever 46 moves from contact with the spring 53 the extra current of self induction accumulates on the plates of the condenser and sparking between the lever 46 80 and spring 53 is thereby obviated.

We claim:

1. The combination with a lever, of a solenoid core connected to said lever, a pin in said lever, a second lever having two arms 85 mounted in the path of said pin, a spring adapted to make contact with one of said arms, and a second spring adapted to hold said second lever in either one of two positions.

2. The combination with a lever, and a solenoid core normally moved downwardly by the force of gravity, of a solenoid and a source of electricity for moving said lever upwardly, a second lever having upper and lower arms, a pin in said first named lever located to strike said upper arm when said first named lever is moved upwardly and move said second lever in one direction and to strike said lower arm and move said second lever in the opposite direction when said first named lever is moved downwardly, and a spring acting upon said second lever to move it slightly after said lower arm has been moved by said pin and to hold said second lever after said upper arm has been moved by said pin.

3. The combination with a lever, and a solenoid core normally moved downwardly by the force of gravity, of a solenoid, a second lever, a pin carried by said first named lever and adapted to move said second lever in two directions, a source of electricity connected to said solenoid for moving said core upwardly, a circuit including said source and said solenoid and having one terminal connected to said second lever, a spring connected to the other terminal of said circuit and adapted to make and break contact with said second lever, and a second spring for holding said second lever at the limit of its movement in either direction.

4. The combination of a time train including a pintle and a ratchet wheel mounted on said pintle, with a lever, a pawl mounted on said lever and adapted to move said ratchet wheel, a solenoid core connected to said lever and moved downwardly by the

force of gravity, a solenoid and a source of electricity connected to said solenoid for moving said core upwardly, a second lever, a pin carried by said first named lever and 5 adapted to move said second lever in two directions, a circuit including said source and said solenoid and having one terminal connected to said second lever, and a spring

connected to the other terminal of said circuit and adapted to make and break contact 10 with said second lever.

In testimony whereof, we affix our signatures.

GUSTAV BLUMBERG.
JOHN A. BUTKUS.
